CLAIM

The ornamental design for a fabric, as shown and described.

DESCRIPTION

FIG. 1 is a top perspective view of a fabric showing my new design;

FIG. 2 is a top plan view;

FIG. 3 is a bottom plan view;

FIG. 4 is a side elevational view thereof; and,

FIG. 5 is another side elevational view thereof; any other side elevational views are the same.

The shading partially shown in the corners of FIG. 3 is continuous throughout.

FIG. 1

FIG. 2

FIG. 3

FIG. 4

FIG. 5
